BY Z. M. Horca, ATTORNEY.

UNITED STATES PATENT OFFICE.

ABE ORNSTEIN KAPLAN, OF CINCINNATI, OHIO.

FLAME-PRODUCING DEVICE.

SPECIFICATION forming part of Letters Patent No. 739,425, dated September 22, 1903.

Application filed March 13, 1903. Serial No. 147,594. (No model.)

To all whom it may concern:

Be it known that I, ABE ORNSTEIN KAPLAN, a citizen of the United States, residing at Cincinnati, in the county of Hamilton and State of Ohio, have invented new and useful Improvements in Flame-Producing Devices, of which the following is a specification.

My invention relates to a novel and useful means of carrying and utilizing materials for producing flame as a substitute for the ordinary matches.

The inconvenience and danger attending the use of matches are sufficiently obvious, besides the liability of fire from carelessness in throwing away the still-lighted match after use.

My invention provides against these disadvantages and furnishes a convenient receptacle for and means of using a combustible globe or pellet made to produce and carry a flame sufficient for all ordinary purposes and leave no inflammable residuum.

To this end my invention consists in a pocket-magazine adapted to carry and feed one by one inflammable pellets, in combination with a grasping and holding device for holding and utilizing the inflamed pellet.

My invention is illustrated in the accompanying drawings, in which—

Figures 1 and 2 are elevations from points of view ninety degrees apart of the magazine or pellet-carrier, showing the holding device utilized as a cap for the magazine. Figs. 3 and 4 are exterior views from the same points of view, showing the position of the carrier in the act of feeding pellets and the holding device in the act of withdrawing a pellet for use. Fig. 5 is a detail view of the pellet and the igniting-plates between which it is passing in the act of ignition.

The magazine A is preferably a hollow tube of about the appearance and dimensions of a "fountain-pen" and adapted to be carried in the same manner. The tube is closed at one end preferably by a removable plug; but it is entirely open at the other end, where project two elastic tongues *a a* at opposite sides of and parallel with the projected axis of the tube. These tongues are so formed as to guide and retain a pellet *p*, issuing from the magazine, and are provided at their outer ends with two toothed or suitably-roughened

plates *b b*, between which the pellet must pass in being drawn outward, the tongues *a* being forced apart against their natural resiliency 55

The holder B for removing, holding, and applying a flaming pellet *a* is also utilized as a cap to close the open end of the magazine A. It is substantially cup-shaped to fit over 60 the end of the magazine A and cover and protect the projecting tongues *a* and has itself two jaws *b b*, projecting at opposite sides of and parallel to its axis and provided with terminals *b' b'*, suitably formed to grasp and 65 securely hold a pellet *a* when the jaws *b b* are forced together against their own resiliency after the manner of a pair of tongs. In the illustration the terminals *b'* are formed as shallow cups to fit and clasp the pellet at opposite sides; but they may be formed as claws 70 for a like purpose.

The pellet as I prefer to manufacture it is a globule of absorbent clay or earthy material charged by absorption with an inflammable liquid and covered by a suitable envelop or coating of such a nature as to constitute an impervious varnish inflammable by friction against a rough surface or one provided with or formed of a suitable chemical element, as in the case of so-called "safety" matches.

The coating in this case serves the double purpose of preserving the absorbed liquid from evaporation and also by its own ignition heating the absorbent matrix, vaporizing and igniting the contained liquid, and causing a more intense and effective combustion.

The mode of operation is fully indicated in 90 the drawings, and is as follows: The magazine A is charged either at the normally open end by temporarily spreading apart the tongues *a* or by temporarily removing the screw-plug *a'* at the normally closed end and 95 inserting the pellets, as indicated in Fig. 3. Supposing the magazine to be thus charged and a light is desired, the magazine is inclined so as to allow the pellets to run toward the open end and the outer one to pass outward between the tongues *a* until stopped by the plates or blocks *a'*. The cover B is removed and held in such position that the tongues *b* may be compressed between the

thumb and forefinger of one hand clasping the pellet between the terminals, as indicated in Figs. 3 and 4. The pellet is then withdrawn directly outward between the 5 roughened or prepared surfaces of the plates *p*, as indicated in Fig. 5, which yield apart through the resiliency of the tongues *a*, but with sufficient frictional pressure against the ignitable coating of the pellet to inflame the 10 latter. The coating being inflamed, the substance of the pellet is heated, thereby vaporizing and causing the expulsion and combustion of the vaporized liquid. The absorbent material may be of a friable nature, so as to 15 be resolved to dust in the operation, if preferred, and the nature and the quantity of the various combustible elements may be arranged to produce the intensity and duration of combustion desired for given purposes.

20 For cigar-lighting purposes the device is especially adapted, as it is conveniently carried in the pocket and used with great con-

venience; but it is equally useful and convenient for all other purposes.

I claim as my invention and desire to secure 25 by Letters Patent of the United States—

A pocket carrier for inflammable pellets consisting of an elongated cylinder or magazine normally open at one end and there provided with opposite resilient tongues having roughened plates or blocks carried by the tongues, in combination with a cap or cover provided with resilient extensions adapted to hold a pellet between their terminals, said cap or cover adapted to fit over and cover the 30 open end and tongues of the magazine, substantially as set forth.

In testimony whereof I have hereunto set my hand in presence of two subscribing witnesses.

ABE ORNSTEIN KAPLAN.
